ABSTRACT OF THE DISCLOSURE

A girdle having a basic body-holding sheath and two pairs of reinforcing auxiliary panels, one of said pairs being partially overlapped at the abdominal area and extending around the thighs to the lower edge of the rear of the basic body sheath and the second pair abutting each other at a seam in the back of the garment and extending around the thighs to the lower front edge of the sheath.

BACKGROUND OF THE INVENTION

Field of the invention

The present invention relates to a foundation garment which provides firm support for the abdomen, thighs and back while retaining its position on the figure during movement.

Description of the prior art

A girdle must provide firm support for particular locations on the figure to ensure the desired cosmetic effect. Three principal locations requiring such support are the abdomen, thighs and lower back. In the past, double-panel girdles have been used to provide the needed support in the locations required, these garments however have tended to be expensive in terms of excess material used. Further, prior art girdles have also increased the discomfort of the wearer by adding additional layers of material to the garment, resulting in a warmer garment and more weight than necessary to produce the desired effect.

The prior girdles have generally been provided with double-layer construction at particular stress points such as the abdomen and other locations on the garment. The prior art girdles have, however, failed to integrate the use of material in the various high stress areas to provide interaction between the supporting elements. Lack of such interaction results in the garment tending to ride up on the figure when movement of the body occurs. In addition the restraining efficiency of the extra material is reduced due to the fact that the double layer is not secured in a manner to effectively transmit stress in the critical areas. Further, the bulk of such garments is unnecessarily great since a large segment of the second layer fails to contribute to the desired effect.

SUMMARY

The girdle of this application eliminates the disadvantages of the prior art girdles and has several additional advantages. Accordingly, the girdle is formed of a basic body surrounding sheath made of a suitable elastic material. Superimposed on the basic sheath are two pairs of reinforcing elements, also made of elastic material.

One pair of reinforcing elements is overlapped at the abdomen. The reinforcing elements are of sufficient strength to restrain the central portion of the abdomen and results in a triple thickness of elastic material at a place of extreme requirement for support.

The second pair of reinforcing elements abut each other at a seam located in the rear of the garment. This pair of elements is sized to provide additional support for the

2

lower back area with a minimum of material in non-stress locations.

Each of the overlapping reinforcing elements, front and rear, further contain an extended arm-like portion which is curved around the body in the area of the thighs and is ultimately terminated at the lower edge of the garment above the garter supports on the opposite side of the garment from the main portion of the element. The thigh surrounding portions provide support against bulging thighs and further add support to the garment at the garter supports preventing sag of the girdle in this area.

The provision, in my girdle, of portions of the reinforcing elements circling the thighs greatly aids the interaction between the abdominal and back reinforcing sections and the thigh supporting sections. The four arms act together so that when the body is twisted the arm-like elements supporting the thighs tend to assist the abdominal and back reinforcing elements, thereby providing extra support. Similarly, during a forward bending movement at the waist the garment effectively restrains the abdomen since the rearwardly extending arm-like elements of the abdominal reinforcing elements assist the abdominal reinforcing elements in a manner to provide additional support. In addition, the back of the garment is restrained from riding up during forward bending due to the presence and action of the two rear areas.

The interrelationship between the actions of the various sections of the improved girdle provides support for the abdomen, back and thighs as well as retaining the shape of the garment when used to support stockings. The effect of the interaction far exceeds the effect of the individual elements acting alone and produces a lightweight garment of high restraining characteristics.

DESCRIPTION OF THE DRAWINGS

The invention will be explained in greater detail below and in the drawings, in which:

FIG. 1 is a front view of the girdle of the invention; FIG. 2 is a rear view of the girdle of FIG. 1; and FIG. 3 is a side view of the girdle of FIG. 1.

DESCRIPTION OF THE PREFERRED EMBODIMENT

Referring to FIG. 1, the girdle of the invention consists of a main body encircling sheath 10 which is made of a suitable elastic material such as one of the variety of artificial fabrics currently available. The main body sheath 10 is provided with a configuration which tends to constrain the lower portion of the torso and give a pleasing configuration to the shape of the body. Sheath 10 has a reinforced opening 11 at the upper end for location at the waist. The reinforcement 11 may consist of an elastic band sewn to the entire edge. A larger dimension across the mid-portion 12 is provided for placement over the buttocks and abdomen and a narrower reinforced opening 13 at the bottom is provided to encircle the thighs. The main body sheath 10 may be a single-molded latex piece or may be composed of several panels sewn together along their edges in conventionally known ways. In the embodiment illustrated a single piece of elastic material suitably woven is sewn together along a seam 29 vertically located in the back of the garment.

The front reinforcing elements 14 and 15 are attached by stitching 16 along their periphery to the main body sheath 10 as shown in FIG. 1. The two elements 14 and 15 are identical to each other and are made of an elastic material that may or may not be the same material as used for body sheath 10. Each of the elements has a large abdominal supporting section 17 and 18 which is overlapped with the complementary portion of its opposite member and sewn together to provide increased support

at the abdomen. By sewing the units together in the manner shown, three layers of elastic material are overlapped providing firm uplifting support for the abdomen and providing more restraint in the local-area than would be present in the absence of the reinforcing elements.

Elements 14 and 15 are further provided with extending arm portions 19 and 20 which are integral with sections 17 and 18 and extend from the abdomen across the thigh area. Arms 19 and 20 both provide firm support for the included thigh area and reduce the tendency toward bulging that occurs in the lower thigh area. Arms 19 and 20 curve downwardly around the thighs and are anchored by sewing at the rear lower edge of the girdle above garters 21 and 22, respectively.

Referring to FIG. 2, two supporting panels 23 and 24 are sewn to the main sheath 10 to provide support for the lower back area. The two panels are separate but abut each other at rear seam 29. Stitching 16 around their entire periphery unites the panels to the main sheath 10 so as to provide an integral structure capable of providing support to the body where needed.

Although panels 23 and 24 are shown as a pair of separate units they can be formed as a single panel in the event that the main body sheath is of the molded or dipped latex type. It has been found, however, that when the main sheath is of a woven fabric and requires a seam 29, it is desirable to assemble the garment using a pair of panels 23 and 24 so that the garment can be completed in a flat condition with the exception of seam 29.

As shown in FIG. 3, each of the rear panels 23 and 24 is also provided with an extending arm 25 and 26 which circles the thighs and provides support for the thigh area. Each of the arms 25 and 26 is terminated at the lower front edge of the garment above garters 27 and 28.

The attachment of the reinforcing elements to the body sheath 10 in the manner shown produces a combined effect that exceeds the effect of the individual elements. The reinforcing elements provide localized resistance to bulging at the abdomen while the wearer is in a vertical position. When the wearer twists from side to side, arms 19, 20, 25 and 26 restrain the side bulging of the thighs since the arms are anchored to the overlapping abdominal panels 17 and 18 and the secured rear panels 23 and 24 and a triple thickness of material is present on both thighs. Further, when the wearer bends forward, arms 19 and 20 act to restrain the thighs and in addition support the abdominal supporting panels 17 and 18.

Arms 19, 20, 25 and 26 further reduce or eliminate sag in the garment caused by stress on the garters 21, 22, 27 and 28 located at the bottom edge of the garment. The garters are located directly below the ends of arms 19, 20, 25 and 26 and are therefore subjected to double support rather than the single support of the main body sheath 10.

It is to be understood that the embodiment described herein is merely by way of illustration and that many modifications can be made in the means for attaching the elements to the body such as by fusing artificial fibers to each other. Further, the specific location of the support elements may be varied, depending on the dimensions and type of basic body sheath. It is also to be understood that while a conventional girdle is described herein the invention is also adaptable to the panty-type girdle.

What is claimed is:

1. A foundation garment comprising in combination a main body encircling and restraining portion and a plurality of supplementary supporting elements attached to said main body encircling portion, each of said supplementary supporting elements having an enlarged portion attached to the main body portion in an area of high stress, said enlarged portions of at least two of said supplementary supporting members partially overlap each other in the abdominal area and are attached to each other and to said main body encircling and restraining portion

and each of said supplementary supporting elements having at least one integral portion extending from said enlarged portion around the side of said garment in the thigh area to the opposite side of said garment.

5 2. A foundation garment according to claim 1, further comprising in combination garters attached to the lower edge of the main body encircling portion, wherein the integral portions extending from the enlarged portion of each of said supplementary supporting elements terminate above the garters to thereby support said garters and reinforce said main body encircling portion when said garters are in use.

10 3. A foundation garment according to claim 1 wherein the enlarged portion of at least one of said plurality of supporting members is located in the rear of the garment to provide support for the lower back area.

15 4. A foundation garment according to claim 1 wherein at least two of said supporting members are located in the rear of the garment to support the lower back area and the integral portion extending from said enlarged portions of each of said supplementary supporting members across each other in the thigh area to provide additional support for the thighs.

20 5. A foundation garment comprising in combination a main body encircling and restraining portion and a plurality of supplementary supporting elements attached to said main body encircling portion, each of said supplementary supporting elements having an enlarged portion attached to the main body portion in an area of high stress and each of said supplementary supporting elements having at least one integral portion extending from said enlarged portion around the side of said garment in the thigh area to the opposite side of said garment, and garters attached to the lower edge of the main body encircling portion, wherein said integral portion extending from said enlarged portion of each of said supplementary supporting elements terminates above the garters to thereby support said garters and reinforce said main body encircling portion when said garters are in use.

25 40 6. A foundation garment according to claim 5 wherein the enlarged portion of at least two of the supporting members overlap each other in the abdominal area and are attached to each other and at least two of the supporting members are located in the rear of the garment to support the lower back area and the integral portion extending from said enlarged portions of each of said supplementary supporting members cross each other in the thigh area to provide additional support for the thighs.

30 7. A foundation garment comprising in combination a main body encircling and restraining portion and a plurality of supplementary supporting elements attached to said main body portion in an area of high stress and each of said supplementary supporting elements having at least one integral portion extending from said enlarged portion around the side of said garment in the thigh area to the opposite side of said garment, at least two of said supporting members being located in the rear of the garment to support the lower back area and said integral portion of said supporting members located in the rear of said garment intersecting with an integral portion from another supplementary supporting member in the thigh area to provide additional support for the thighs.
